MANUALLY OPERATED HOIST

Joseph J. Hite, St. Paul, Minn., assignor to
American Hoist & Derrick Co., St. Paul, Minn.,
a corporation of Delaware

Application May 29, 1944, Serial No. 537,895

13 Claims. (Cl. 254—186)

1

This invention relates to a material handling apparatus constituted as a hoist adapted to be manually operated.

An object of the invention is to provide a simply constructed, efficient, novel and improved manually operable hoist equipped to be selectively operated at different speeds.

A further object is to provide a material handling apparatus wherein will be incorporated various improved features and characteristics of construction novel both as individual entities of the material handling apparatus and in combination with each other.

And a further object is to provide a material handling apparatus constituted as a hoist constructed as hereinafter set forth and adapted to be manually operated selectively at different speeds.

With the above objects in view, as well as others which will appear as the specification proceeds, the invention comprises the construction, arrangement and combination of parts as now to be fully described and as hereinafter to be specifically claimed, it being understood that the disclosure herein is merely illustrative and intended in no way in a limiting sense, changes in details of construction and arrangement of parts being permissible so long as within the spirit of the invention and the scope of the claims which follow.

In the accompanying drawings forming a part of this specification,

Fig. 1 is a side elevational view, partially in section and partially broken away, of a material handling apparatus or hoist made according to the invention, as said apparatus or hoist would appear from the right in Fig. 3;

Fig. 2 is a side elevational view of the material handling apparatus or hoist as it would appear from the left in said Fig. 3;

Fig. 3 is a front elevational view of the material handling apparatus;

Fig. 4 is a vertical, longitudinal sectional view, taken substantially as on line 4—4 in Fig. 1; and

Fig. 5 is a detail view of a hand crank assembly adapted to be employed to the accomplishment of manual operation of the material handling apparatus or hoist.

With respect to the drawings and the numerals of reference thereon, a base for the material handling apparatus is constituted as a right side frame 10 and a left side frame 11.

The right side frame 10 consists of a body 12 including supports 13 for said right side frame 10 integral with said body 12. The body 12 also

2

integrally includes a cylindrical bearing member 14 providing an external bearing surface 15, and said body 12 integrally supports an upper bearing 16, above the elevation of the cylindrical bearing member 14, and a lower bearing 17, at the elevation of the lower portion of said cylindrical bearing member 14. The upper bearing 16, the cylindrical bearing member 14 and the lower bearing 17 are as disclosed in substantially vertical alignment, said lower bearing 17 is disposed somewhat inwardly of said upper bearing 16, and said cylindrical bearing member 14 is disposed inwardly of both of the upper and lower bearings 16 and 17. The upper bearing 16 provides an internal bearing surface 18 and the lower bearing 17 provides an internal bearing surface 19. The external bearing surface 15 and the internal bearing surfaces 18 and 19 are all in parallel relation, and each of the upper bearing 16, the cylindrical bearing member 14 and the lower bearing 17 is as shown disposed substantially horizontally. The cylindrical bearing member 14 with external bearing surface 15, the upper bearing 16 with internal bearing surface 18 and the lower bearing 17 with internal bearing surface 19 all extend longitudinally of the material handling apparatus in the disclosure as made. Openings 20 in the supports 13 of the right side frame 10 are for receiving means (not shown), such as bolts, for anchoring said right side frame 10 to a suitable supporting structure for the material handling apparatus.

The left side frame 11 consists of a body 21 including supports 22 for said left side frame 11 integral with said body 21. The body 21 also integrally includes a cylindrical bearing member 23 providing an external bearing surface 24. Said cylindrical bearing member 23 is in aligned, spaced relation to the cylindrical bearing member 14, and the external bearing surfaces 15 and 24 are also aligned in direction longitudinally of the material handling apparatus. Openings 25 in the supports 22 of the left side frame 11 are for receiving anchoring means (not shown) for said left side frame 11.

A drum of the material handling apparatus is constituted as a right drum entity 26 and a left drum entity 27 suitably secured to each other and rotatably supported upon the cylindrical bearing members 14 and 23 of the right and left side frames 10 and 11, respectively.

The right drum entity 26 consists of a body shaped to provide an annular member 28 at the inner side of said body disposed transversely of the drum, a cylindrical bearing member 29 in-

tegral with and extending outwardly from said annular member 28 and an annular flange member 30 integral with and extending exteriorly from the outer end of said cylindrical bearing member 29. The annular flange 30 is as shown arranged at right angle relation to the cylindrical bearing member 29, and said cylindrical bearing member 29 includes an internal bearing surface 31.

The left drum entity 27 consists of a body shaped to provide an annular member 32 at the inner side of said body disposed transversely of the drum, a cylindrical bearing member 33 integral with and extending outwardly from said annular member 32 and an annular flange member 34 integral with and extending exteriorly from the outer end of said cylindrical bearing member 33. The annular flange member 34 is as shown arranged at right angle relation to the cylindrical bearing member 33, and said cylindrical bearing member 33 includes an internal bearing surface 35.

Actually, the right and left drum entities 26 and 27 are, or may be, substantially alike. To the provision of the finished drum, adjacent surfaces of the annular, transverse members 28 and 32 of said right and left drum entities 26 and 27 are placed in abutting relation, so that the cylindrical bearing members 29 and 33 are in alinement, and welded, or otherwise secured, to each other. The relation of the right and left drum entities to each other in the completed drum is very clearly disclosed in Fig. 4 of the drawings.

The annular, transverse members 28 and 32 of the right and left drum entities 26 and 27 are shaped to provide a concavity 36 between said members 28 and 32 for receiving the end portion of a cable 37 for the drum, and an anchor for said cable 37 is constituted as a fixing screw 38 threaded into said drum at the location where said right and left drum entities meet and adapted to be turned down into the concavity 36 against the drum cable 37.

The body 12 of the right side frame 10 integrally includes an annular member 39 disposed transversely of said right side frame 10, and the body 21 of the left side frame 11 likewise includes an annular member 40 disposed transversely of said left side frame 11. More explicitly, the annular, transverse members 39 and 40 are integral with the inner ends of the cylindrical bearing members 14 and 23, respectively. Said annular transverse members 39 and 40 are in spaced relation to each other, the annular, transverse members 28 and 32 are disposed between and in spaced relation to the annular, transverse members 39 and 40, and the internal bearing surfaces 31 and 35 of the hoist drum are upon annular bushings 49 carried by the external bearing surfaces 15 and 24 of the cylindrical bearing members 14 and 23, respectively, when said drum is in assembled relation to the right and left side frames 10 and 11.

Said right and left side frames 10 and 11 are securely fastened to each other by spaced apart, relatively long spacer and tie rods 41, 41 which extend from side to side of the material handling apparatus, through the bodies 12 and 21 of the right and left side frames, and receive nuts 42 upon their threaded reduced outer end portions 43, as well as by a relatively short spacer and tie rod 44 which extends centrally through the annular, transverse members 39 and 40 and receives nuts 45 upon its threaded reduced outer end portions 46. The construction and arrange-

ment are such that the reduced outer end portions 43 provide annular shoulders at the opposite ends of the relatively long spacer and tie rods 41, and the nuts 42 retain the right and left side frames up against said annular shoulders of said spacer and tie rods 41. That is to say, the rods 41 cooperate with the nuts 42 to retain lower portions of the right and left side frames in fixed relation to each other. The construction and arrangement are also such that the reduced outer end portions 46 provide annular shoulders at the opposite ends of the relatively short spacer and tie rod 44, and the nuts 45 retain the annular, transverse members 39 and 40 of the right and left side frames up against said annular shoulders of the spacer and tie rod 44. Stated otherwise, the rod 44 cooperates with the nuts 45 to retain intermediate portions of said right and left side frames in fixed relation to each other. It will be seen that the side frames 10 and 11 are rigidly held to each other by what may be termed a three point bolting. As disclosed, the spacer and tie rods 41, 41 are situated at lower, forward and rearward locations of the material handling apparatus, and the spacer and tie rod 44 is situated at much higher location, substantially equidistantly spaced from said spacer and tie rods 41, 41 and from the front and rear of the apparatus.

The spacer and tie rod 44 passes through an opening 47 arranged centrally in the annular, transverse members 28 and 32 of the drum entities 26 and 27, and annular spacers 48, 48, upon said spacer and tie rod 44 and between the annular, transverse members 28, 39 and 32, 40, respectively, retain the hoist drum at its intended or centered location longitudinally of the material handling apparatus. That is, the hoist drum is mounted upon the annular bushings 49, themselves mounted upon the cylindrical bearing members 14 and 23 of the right and left side frames 10 and 11, to be freely rotatable upon said right and left side frames, and said hoist drum is also held against the possibility of movement in direction longitudinally of the apparatus.

The lower bearing 17 integrally carried by the body 12 of the right side frame 10 rotatably supports, as at 50, a hollow stud shaft 51, which hollow stud shaft in turn integrally supports a brake drum 52 in surrounding relation to the stud shaft and a pinion 53 at the outer side of and alined with said lower bearing 17. The hollow stud shaft 51 and the pinion 53, constituting a continuation of said hollow stud shaft, include an angular socket 54 for removably receiving an angular tool 55 of a hand crank assembly 56 for operating the material handling apparatus. As disclosed, the handle of the hand crank assembly 56 is adjustable as to length.

The upper bearing 16 integrally carried by the body 12 of said right side frame 10 rotatably supports, as at 57, a hollow shaft 58, which hollow shaft in turn integrally supports a large intermediate gear 59 at the outer end or side of the upper bearing 16 and a small intermediate gear 60 at the inner end or side of said upper bearing. The large intermediate gear 59 is in surrounding, perpendicular relation to the hollow shaft 58, and the small intermediate gear 60 is alined with said hollow shaft 58. Said hollow shaft 58, the large intermediate gear 59 and the small intermediate gear 60 include an angular socket 61 for removably receiving said angular tool 55 of said hand crank assembly 56.

The pinion 53 meshes with the large intermediate gear 59, and said pinion and said large intermediate gear provide what may be termed a first speed reduction gearing arrangement of the material handling apparatus.

The annular flange member 30, constituted as a part of the body of the right drum entity 26, integrally supports an internal gear 62 which is in surrounding relation to the small intermediate gear 60. Said small intermediate gear 60 meshes with the internal gear 62, and the small intermediate gear and said internal gear provide what may be termed a second speed reduction gearing arrangement of the material handling apparatus.

A brake band 63, with brake lining 64, upon the brake drum 52 has one of its end portions 65 anchored, as at 66, to the body 12 of the right side frame 10 and its other end portion, including a brake band holder 67, pivoted, as at 68, to an intermediate portion of a brake lever 69 situated at the outer side of and having a portion of its length engaged up against said body 12. Said brake band holder 67 passes freely through the body 12. The brake obviously can be applied by manual swinging of the brake lever 69 in direction away from the right side frame, and said brake will be released upon release of said brake lever.

A toothed portion 70 upon the brake drum 52 is adapted to be engaged by a pawl 71 to preclude retrograde movement of said brake drum and the hollow stud shaft. The pawl 71 is rotatably mounted, as at 72, upon one of the spacer and tie rods 41, beneath a nut 42, and the free end 73 of said pawl 71 is spring-pressed toward the toothed portion 70 by a compression spring 74 upon a post 75 rigid with said pawl. The post 75 passes freely outwardly through the body 12 of the right side frame 10, and the compression spring 74 has one of its ends engaged against the pawl and its other end engaged against an inner surface of said body 12. The end of said post 75 spaced from the pawl is pivoted, as at 76, to an intermediate portion of a hand lever 77 for operating said pawl. When the pawl 71 is engaged with the toothed portion 70, a side edge of the hand lever 77 is up against the outer surface of the body 12, or up against a washer between said outer surface of said body 12 and said hand lever. Said pawl can be renewed from said toothed portion by swinging the hand lever 77 outwardly, against resilient action of the compression spring 74. And the pawl can be held removed from the toothed portion, when this is intentional, in any suitable and convenient manner, as by upsetting the hand lever 77 so that its lower end, instead of its side edge, is engaged against the outer surface of the body 12, or against a washer upon said outer surface, as will be understood.

The hollow stud shaft 51, integrally supporting the brake drum 52 and the pinion 53, may be fixed against the possibility of longitudinal movement in the lower bearing 17, integrally carried by the body 12 of the right side frame 10, in any suitable and convenient manner.

The hollow shaft 58, integrally supporting the large intermediate gear 59 and the small intermediate gear 60, includes spaced apart circumferential slots, denoted 78 and 79, the circumferential slot 78 being situated in the end portion of said hollow shaft 58 adjacent said large intermediate gear 59 and the circumferential slot 79 being situated in the end portion of the hollow

shaft adjacent said small intermediate gear 60. The upper bearing 16, integrally carried by the body 12 of the right side frame 10, includes an elongated slot 80, in the upper portion of said upper bearing 16 as disclosed, which is situated adjacent the outer or free end of the upper bearing and extends circumferentially of said upper bearing. Said hollow shaft 58 is adapted to be adjusted longitudinally in the upper bearing 16. More explicitly, the hollow shaft 58 is capable of adjustment in said upper bearing 16 to the position as in Fig. 4 of the drawings, where the small intermediate gear 60 is in mesh with the internal gear 62 and the circumferential slot 78 and the elongated slot 80 are aligned, or to position where said small intermediate gear 60 is clear of said internal gear 62 and the circumferential slot 79 and said elongated slot 80 are aligned. A device for locking said hollow shaft 58 against the possibility of longitudinal movement in the upper bearing 16, either in the position as in Fig. 4, or in a position where the small intermediate gear 60 and the internal gear 62 are disengaged and the circumferential slot 79 and the elongated slot 80 are aligned, is constituted as a retainer lever 81 adapted to lie in said elongated slot 80 and to be selectively insertable into the circumferential slots 78 and 79. A tension spring 82, which encircles the upper bearing 16 and has its opposite ends connected, as at 83, to the retainer lever, is for urging said retainer lever into the elongated slot 80 and toward the hollow shaft 58. In Fig. 4, said retainer lever is in the slots 78 and 80, thus to preclude longitudinal movement of said hollow shaft 58. When it is desired to adjust the hollow shaft to position causing the small intermediate gear 60 to be clear of the internal gear 62, the retainer lever will be swung outwardly a distance to cause it to be removed from the circumferential slot 78, said hollow shaft will be slid outwardly in the upper bearing 16 until the slot 79 is aligned with the slot 80, and the retainer lever will then be released. Said retainer lever will when released position itself in said slots 79 and 80, thus to preclude longitudinal movement of the hollow shaft 58. Clearly, the hollow shaft can be adjusted back to position where the small intermediate gear 60 and the internal gear 62 are interengaged by withdrawing the retainer lever 81 from the slot 79, sliding said hollow shaft inwardly until the slots 78 and 80 are aligned and then releasing said retainer lever.

The tool 55 of the hand crank assembly 56 will be placed in the angular slot 54 when advantage is to be taken of both speed reduction gearing arrangements of the material handling apparatus. That is, the drive of the hoist drum will be through the pinion 53, the large intermediate gear 59, the small intermediate gear 60 and the internal gear 62 for low speed, high power operation of said hoist drum.

Said tool 55 of the hand crank assembly 56 will be placed in the angular socket 61 when advantage is to be taken of but one of the speed reduction gearing arrangements of the material handling apparatus. That is, the drive of the hoist drum will be through the small intermediate gear 60 and the internal gear 62 for high speed, low power operation of said hoist drum. The hollow stud shaft 51, and the brake drum 52 and the pinion 53 integral with said hollow stud shaft 51, will rotate idly when rotative effort is applied at the angular socket 61 without adding to any appreciable extent to the load.

The hoist drum evidently can be freely rotated

so that the cable 37 can be paid off quickly, as when said cable is to be attached to a load to be handled, while the internal gear 62 integral with said hoist drum is disengaged from the small intermediate gear 63 integral with the hollow shaft 58. Unloading, or letting a load down by gravity, obviously can be accomplished by appropriate employment of the brake, operative upon the hollow stud shaft 54, while the pawl 71 is removed from the toothed portion 70.

What is claimed is:

1. Material handling apparatus comprising a base constituted as right and left side frames each consisting of a body providing a cylindrical bearing member, means securing said right and left side frames in fixed relation to each other with said cylindrical bearing members in alignment, a hoist drum rotatably supported upon said cylindrical bearing members of the right and left side frames, a hollow stud shaft adapted to be rotated, a hollow shaft adapted to be rotated, spaced apart bearings upon one of said side frames for said hollow stud shaft and said hollow shaft, a brake drum and a pinion rigid with said hollow stud shaft, a brake band upon said brake drum, means for actuating said brake band, a large intermediate gear and a small intermediate gear rigid with said hollow shaft, said pinion being adapted to engage said large intermediate gear, and an internal gear rigid with said hoist drum adapted to be engaged by said small intermediate gear.

2. Material handling apparatus comprising a base constituted as right and left side frames each consisting of a body providing a cylindrical bearing member, means securing said right and left side frames in fixed relation to each other with said cylindrical bearing members in alignment, a hoist drum rotatably supported upon said cylindrical bearing members of the right and left side frames, a hollow stud shaft adapted to be rotated, a hollow shaft adapted to be rotated, spaced apart bearings upon one of said side frames for said hollow stud shaft and said hollow shaft, a brake drum and a pinion rigid with said hollow stud shaft, a brake band upon said brake drum, means for actuating said brake band, a toothed portion rigid with said brake drum, a pawl upon one of said side frames adapted to be engaged with and disengaged from said toothed portion, a large intermediate gear and a small intermediate gear rigid with said hollow shaft, said pinion being adapted to engage said large intermediate gear, and an internal gear rigid with said hoist drum adapted to be engaged by said small intermediate gear.

3. Material handling apparatus comprising a base constituted as right and left side frames each consisting of a body providing a cylindrical bearing member, means securing said right and left side frames in fixed relation to each other with said cylindrical bearing members in alignment, a hoist drum constituted as right and left drum entities each consisting of a body providing a member at the inner side of said body of the corresponding drum entity disposed transversely of said drum, a cylindrical bearing member integral with and extending outwardly from said transverse member and mounted upon a cylindrical bearing member of one of said side frames and an annular flange member integral with and extending transversely of and exteriorly from a portion of said cylindrical bearing member of the corresponding drum entity, said transverse members of the right and left drum entities being

secured to each other and the cylindrical bearing members of said right and left drum entities being in alignment, and means for causing said hoist drum to be rotated.

4. Material handling apparatus comprising a base constituted as right and left side frames each consisting of a body providing a cylindrical bearing member, means securing said right and left side frames in fixed relation to each other with said cylindrical bearing members in alignment, a hoist drum constituted as right and left drum entities each consisting of a body providing an annular member at the inner side of said body of the corresponding drum entity disposed transversely of said drum, a cylindrical bearing member integral with and extending outwardly from said annular, transverse member and mounted upon a cylindrical bearing member of one of said side frames and an annular flange member integral with and extending transversely of and exteriorly from a portion of said cylindrical bearing member spaced from the annular, transverse member of the corresponding drum entity, said annular, transverse members of the right and left drum entities being secured to each other and the cylindrical bearing members of said right and left drum entities being in alignment, means centering said hoist drum upon the right and left side frames of said base, and means for causing said hoist drum to be rotated.

5. Material handling apparatus comprising a base constituted as right and left side frames each consisting of a body providing a cylindrical bearing member, means securing said right and left side frames in fixed relation to each other with said cylindrical bearing members in alignment, a hoist drum constituted as right and left drum entities each consisting of a body providing an annular member at the inner side of said body disposed transversely of said drum, a cylindrical bearing member integral with and extending outwardly from said annular, transverse member and mounted upon a cylindrical bearing member of one of said side frames and an annular flange member integral with and extending transversely of and exteriorly from a portion of said cylindrical bearing member spaced from said annular, transverse member of the corresponding drum entity, said annular, transverse members of the right and left drum entities being secured up against each other and being situated between the cylindrical bearing members of said right and left side frames, means centering said hoist drum upon the right and left side frames of said base, and means for causing the hoist drum to be rotated.

6. Material handling apparatus comprising a base constituted as right and left side frames each consisting of a body providing a cylindrical bearing member, means securing said right and left side frames in fixed relation to each other with said cylindrical bearing members in alignment, a hoist drum constituted as right and left drum entities each consisting of a body providing an annular member at the inner side of said body disposed transversely of said drum, a cylindrical bearing member integral with and extending outwardly from said annular, transverse member and mounted upon a cylindrical bearing member of one of said side frames and an annular flange member integral with and extending transversely of and exteriorly from a portion of said cylindrical bearing member spaced from said annular, transverse member of the corresponding drum entity, said annular transverse members of the

right and left drum entities being secured to each other and being situated between the cylindrical bearing members of said right and left side frames, a hollow pinion adapted to be rotated, means rotatably supporting said hollow pinion, a hollow shaft adapted to be rotated, a large intermediate gear and a small intermediate gear rigid with said hollow shaft, said pinion being adapted to engage said large intermediate gear, and an internal gear rigid with one of the annular flange members of said hoist drum adapted to be engaged by said small intermediate gear.

7. Material handling apparatus comprising a base constituted as right and left side frames each consisting of a body providing a cylindrical bearing member, means securing said right and left side frames in fixed relation to each other with said cylindrical bearing members in alinement, a hoist drum constituted as right and left drum entities each consisting of a body providing an annular member at the inner side of said body disposed transversely of said drum, a cylindrical bearing member integral with and extending outwardly from said annular, transverse member and mounted upon a cylindrical bearing member of one of said side frames and an annular flange member integral with and extending transversely of and exteriorly from a portion of said cylindrical bearing member spaced from said annular, transverse member of the corresponding drum entity, said annular, transverse members of the right and left drum entities being secured up against each other and being situated between the cylindrical bearing members of said right and left side frames, means centering said hoist drum upon the right and left side frames of said base, a hollow stud shaft adapted to be rotated, a hollow shaft adapted to be rotated, spaced apart bearings upon one of said side frames for said hollow stud shaft and said hollow shaft, a pinion rigid with said hollow stud shaft, a large intermediate gear and a small intermediate gear rigid with said hollow shaft, said pinion being adapted to engage said large intermediate gear, and an internal gear rigid with one of the annular flange members of said hoist drum adapted to be engaged by said small intermediate gear.

8. Material handling apparatus comprising a base constituted as right and left side frames each consisting of a body providing a cylindrical bearing member, means securing said right and left side frames in fixed relation to each other with said cylindrical bearing members in alinement, a hoist drum constituted as right and left drum entities each consisting of a body providing an annular member at the inner side of said body disposed transversely of said drum, a cylindrical bearing member integral with and extending outwardly from said annular, transverse member and mounted upon a cylindrical bearing member of one of said side frames and an annular flange member integral with and extending transversely of and exteriorly from a portion of said cylindrical bearing member spaced from said annular, transverse member of the corresponding drum entity, said annular, transverse members of the right and left drum entities being secured up against each other and being situated between the cylindrical bearing members of said right and left side frames, a hollow stud shaft adapted to be rotated, a hollow shaft adapted to be rotated, spaced apart bearings upon one of said side frames for said hollow stud shaft and said hollow shaft, a brake

drum and a pinion rigid with said hollow stud shaft, a brake band upon said brake drum, means for actuating said brake band, a large intermediate gear and a small intermediate gear rigid with said hollow shaft, said pinion being adapted to engage said large intermediate gear, and an internal gear rigid with said hoist drum adapted to be engaged by said small intermediate gear.

9. In material handling apparatus, the combination with right and left side frames providing spaced apart, alined cylindrical bearing members, of a hoist drum including spaced apart, alined cylindrical bearing members rotatably supported upon and a transverse member between and in spaced relation to said cylindrical bearing members of said right and left side frames, and means engaging said right and left side frames and said transverse member for retaining said hoist drum against longitudinal movement.

10. Material handling apparatus comprising a base constituted as right and left side frames each consisting of a body providing a cylindrical bearing member, means securing said right and left side frames in fixed relation to each other with said cylindrical bearing members in alinement, a hoist drum rotatably supported upon said cylindrical bearing members of the right and left side frames, a stud shaft adapted to be rotated, a shaft adapted to be rotated, spaced apart bearings upon one of said side frames for said stud shaft and said shaft, a brake drum and a pinion rigid with said stud shaft, a brake band upon said brake drum, means for actuating said brake band, a toothed portion rigid with said brake drum, a pawl upon one of said side frames adapted to be engaged with and disengaged from said toothed portion, a large intermediate gear and a small intermediate gear rigid with said shaft, said pinion being adapted to engage said large intermediate gear, and an internal gear rigid with said hoist drum adapted to be engaged by said small intermediate gear.

11. Material handling apparatus comprising a base constituted as right and left side frames each consisting of a body providing a cylindrical bearing member, means securing said right and left side frames in fixed relation to each other with said cylindrical bearing members in alinement, a hoist drum constituted as right and left drum entities each consisting of a body providing an annular member at the inner side of said body disposed transversely of said drum, a cylindrical bearing member integral with and extending outwardly from said annular, transverse member and mounted upon a cylindrical bearing member of one of said side frames and an annular flange member integral with an extending transversely of and exteriorly from a portion of said cylindrical bearing member spaced from said annular, transverse member of the corresponding drum entity, said annular, transverse members of the right and left drum entities being secured to each other and being situated between the cylindrical bearing members of said right and left side frames, a pinion adapted to be rotated, means rotatably supporting said pinion, a hollow shaft adapted to be rotated, a large intermediate gear and a small intermediate gear rigid with said hollow shaft, said pinion being adapted to engage said large intermediate gear, and an internal gear rigid with one of the annular flange members of said hoist drum adapted to be engaged by said small intermediate gear.

12. Material handling apparatus comprising a base constituted as right and left side frames

each consisting of a body providing a cylindrical bearing member, means securing said right and left side frames in fixed relation to each other with said cylindrical bearing members in alinement, a hoist drum constituted as right and left drum entities each consisting of a body providing an annular member at the inner side of said body disposed transversely of said drum, a cylindrical bearing member integral with and extending outwardly from said annular, transverse member and mounted upon a cylindrical bearing member of one of said side frames and an annular flange member integral with and extending transversely of and exteriorly from a portion of said cylindrical bearing member spaced from said annular, transverse member of the corresponding drum entity, said annular, transverse members of the right and left drum entities being secured up against each other and being situated between the cylindrical bearing members of the right and left side frames, means centering said hoist drum upon the right and left side frames of said base, a stud shaft adapted to be rotated, a shaft adapted to be rotated, spaced apart bearings upon one of said side frames for said stud shaft and said shaft, a pinion rigid with said stud shaft, a large intermediate gear and a small intermediate gear rigid with said shaft, said pinion being adapted to engage said large intermediate gear, and an internal gear rigid with one of the annular flange members of said hoist drum adapted to be engaged by said small intermediate gear.

13. Material handling apparatus comprising a base constituted as right and left side frames consisting of a body providing a cylindrical bearing member, means securing said right and left side frames in fixed relation to each other with said cylindrical bearing members in alinement, a hoist drum constituted as right and left drum entities each consisting of a body providing an annular member at the inner side of said body disposed transversely of said drum, a cylindrical bearing member integral with and extending out-

wardly from said annular, transverse member and mounted upon a cylindrical bearing member of one of said side frames and an annular flange member integral with and extending transversely of and exteriorly from a portion of said cylindrical bearing member spaced from said annular, transverse member of the corresponding drum entity, said annular, transverse members of the right and left drum entities being secured up against each other and being situated between the cylindrical bearing members of said right and left side frames, a stud shaft adapted to be rotated, a shaft adapted to be rotated, spaced apart bearings upon one of said side frames for said stud shaft and said shaft, a brake drum and a pinion rigid with said stud shaft, a brake band upon said brake drum, means for actuating said brake band, a large intermediate gear and a small intermediate gear rigid with said shaft, said pinion being adapted to engage said large intermediate gear, and an internal gear rigid with said hoist drum adapted to be engaged by said small intermediate gear.

JOSEPH J. HITE.
